UNITED STATES PATENT OFFICE

168,774

TEXTILE FABRIC

Edward White, IV., Cranford, N. J., assignor to Chicopee Mills, Inc., a corporation of New York

Application August 13, 1952, Serial No. 21,019

Term of patent 14 years

(Cl. D92—1)

To all whom it may concern:

Be it known that I, Edward White, IV, a citizen of the United States, residing at Cranford, in the county of Union, State of New Jersey, have invented a new, original, and ornamental Design for a Textile Fabric, of which the following is a specification, reference being had to the accompanying drawing, forming a part hereof, in which the figure is a plan view of a textile fabric showing my new design.

I claim:

The ornamental design for a textile fabric, as shown.

EDWARD WHITE, IV.
